UNITED STATES PATENT OFFICE.

ALONZO A. COBURN, OF LOWELL, MASSACHUSETTS.

MACHINE FOR OPENING AND WORKING FIBROUS MATERIALS.

SPECIFICATION forming part of Letters Patent No. 598,284, dated February 1, 1898.

Application filed September 22, 1897. Serial No. 652,647. (No model.)

To all whom it may concern:

Be it known that I, ALONZO A. COBURN, a citizen of the United States, residing at Lowell, in the county of Middlesex and Commonwealth of Massachusetts, have invented a certain new and useful Improvement in Machines for Opening and Working Fibrous Materials, of which the following is a specification.

10 My invention relates to machines for opening and working fibrous materials, as openers, lappers, carding-engines, &c., in which the stock is carried to the feed-rolls between yielding evener-plates and a fluted evener-roll by the rotation of said fluted roll. Said stock is fed between such evener-roll and evener-plates in the form of laps or sheets of fiber, usually two or more laps being placed one upon another to form a compound lap, 15 so that if the friction of the plates upon one face of a single or compound lap is too great (owing to any roughness of the plates or to electrical attraction of the fibers by the plates) the other face of the stock will travel 20 faster than the bottom thereof and said stock will be crimped or rolled into irregular masses, rendering the evening devices useless.

The object of this invention is to feed the layer of stock while between the evener-roll 30 and the evener-plates so that both faces of said layer shall travel at the same speed.

To this end I use certain feed-wheels having their centers of rotation on the opposite side of the plates from the evener-roll, the 35 curved surfaces of said wheels projecting through said plates and being adapted to engage fibers passing between said evener-roll and said plates and said wheels having substantially the same surface speed as that of 40 said evener-roll.

In the accompanying drawings on five sheets, Figure 1 is a left side elevation of a cotton opener and lapper, showing such parts of the frame, driving mechanism, and even- 45 ing devices as are necessary to the explanation of the invention; Fig. 2, an enlarged right side elevation of the same with the sprocket wheels and chain by which a counter-shaft is driven to rotate the feed-wheels; Fig. 3, a vertical longitudinal section of a 50 part of the feed-apron, feed-rolls, evening devices, and my improvement on the line 3 3 in

Fig. 4; Fig. 4, a plan of the parts shown in Fig. 3, a part of the feed-apron being broken away; Fig. 5, a vertical transverse section on the line 5 5 in Fig. 3; Fig. 6, a similar section showing a modification of what is shown in Fig. 5; Fig. 7, a vertical section on the line 7 7 in Fig. 6 of the evener-roll, also showing a feed-wheel and its supporting-lever in 60 side elevation; Fig. 8, a front elevation, partly in vertical central section, of two of the feed-wheels shown in Fig. 6 connected by links; Fig. 9, a right side elevation similar to Fig. 2, but omitting the sprocket wheels and chain 65 and showing a modification of the means of driving the feed-wheels; Fig. 10, a plan of the feed-rolls, evener-roll, evener-plates, and feed-wheels with the means of driving the feed-wheels shown in Fig. 9, Figs. 11, 12, and 70 13 representing modifications, Fig. 11 a front elevation, partly in vertical section, on the line 11 11 in Fig. 13, Fig. 12 a plan of the evener-plates and feed-wheels shown in Fig. 11, and Fig. 13 a side elevation of an evener- 75 plate and feed-wheel and a vertical section of the feed-rolls and evener-roll on the line 13 13 in Fig. 11.

The frame A, apron sides a a', feed-apron B, rear apron-roll b, evener-roll C, evener- 80 plates D, having extensions d, each of which is connected through a system of scale-levers in the usual manner to a shipper-lever E, which moves the belt F up or down upon the cones G G' to vary the relative speed of said 85 cones and therefore the speed of the feed-rolls H H', according to the average thickness of the sheet of fibers at any time passing between the evener-roll and evener-plates. All these parts are of the usual construction and operation except as hereinafter stated.

It will be understood by those skilled in the art to which this invention relates that the power to drive the machine is applied by a belt (not shown) to a pulley i, fast on the 95 beater-shaft I; that a belt k from another pulley i', also fast on said beater-shaft, drives a pulley K and through the bevel-gear k', fast on said pulley K, the bevel-gears l l', fast on the side shaft L, and another bevel-gear g, 100 fast on the shaft of the driving-cone G, drives said cone G; that a worm g' on the shaft of the driven cone G' drives the worm-wheel c, fast on the evener-roll C, Figs. 1 and 2; that

the feed-rolls H H' are connected to each other by gears h h', Figs. 2 and 4; that another gear h³, fast on the feed-roll H, is driven by a gear c' on the evener-roll C, and that another gear c², fast on the evener-roll, engages a gear b' on the shaft b² of the rear apron-roll b.

To prevent the lap or sheet of stock from adhering to the evener-plates, I arrange a shaft P transversely of the machine below

- 10 and parallel with said evener-plates, supporting said shaft P in the rear forked ends of two equal parallel levers J, pivoted at j' on the inner faces of the opposite sides of the frame, the front arms j² of said levers carrying weights J', adjustable on said front arms by means of notches j³ in said front arms, and on said shaft P, I secure feed-wheels p, the curved faces p' of which are roughened or preferably fluted at p² to correspond with the
- 15 fluted surface of the evener-roll. The feed-wheel shaft P is provided near its ends with sprocket-wheels p³ p³, fast thereon, and connected by sprocket-chains Q Q to other sprocket-wheels m m, fast on a counter-shaft 20 M, journaled in the frame A of the machine parallel with the evener-roll C. On one end of the counter-shaft M is another sprocket-wheel m', connected by a chain N to a sprocket-wheel O, fast on the shaft b² of the rear apron-roll b. The numbers of teeth in the sprocket-wheels p³, p³, m, m, m', and O are such as to give to the feed-wheels a surface speed substantially equal to the surface speed of the evener-roll.
- 25 35 The feed-wheels p project through the evener-plates D, which are cut away at d' for that purpose, to or nearly to the evener-roll when there is no stock in the machine.

When the stock is passing between the

- 40 evener-roll and the evener-plates, the latter are depressed in the usual manner and allow the roughened, toothed, or fluted surfaces of the feed-wheels to engage the fibers and carry the surface of the lap farthest from the evener-roll at the same speed as the surface speed of said lap nearest to said evener-roll and thus prevent the crimping or rolling of the fibers on each other and the matting of the fibers between the evener-roll and evener-plates.
- 45 50 The slight movement of the feed-wheels toward and from the evener-roll, due to the varying thickness of the sheet of stock between said wheels and evener-roll, does not affect the position of the belt F on the cones G G', nor the speed of the evener-roll and feed-rolls, which is controlled, as heretofore, entirely by the position and movement of the evener-plates.

- In Figs. 6, 7, and 8 the feed-wheels (which
- 60 are like the feed-wheels p, Figs. 1 to 5, except as hereinafter stated) are represented as supported independently of each other to allow each feed-wheel to exert substantially the same pressure upon the stock between such feed-roll and the evener-roll.

In the figures last named each feed-wheel p⁴ is represented as provided with hubs p⁵,

which rest in suitable bearings upon the forked rear end of a lever J², which turns upon a horizontal fulcrum-shaft j⁴ and may 70 be weighted, having for that purpose notches j³ and being like the lever J, except as above stated, the intervals between the levers J² on the shaft j⁴ being maintained by collars j⁵, secured in place by set-screws or any usual 75 means.

The feed-wheels in Figs. 6 to 8 are represented as connected by links j⁶, provided with enlarged ball-shaped ends j⁷, having diametrical slots j⁸, the slots in opposite ends of the 80 same link being at right angles to each other and the ends j⁷ entering the hollow hubs p⁵ of adjacent feed-wheels p⁴, which are caused to rotate with said links by pins p⁶, which pass diametrically through said hubs p⁵ and slots j⁸ in such a manner as to allow said feed-wheels independently of each other a slight movement toward and from the evener-roll. The outer hubs of the feed-wheels p⁴ at the 85 ends of the series of feed-wheels are provided with sprocket-wheels p³ p³ of the same construction and operation as those shown in Figs. 1 to 5.

The movement of the sprocket-wheels p³ p³ away from the evener-roll in either of the 90 constructions above described is so slight as not to disengage the sprocket-chains from the wheels connected by them.

In Figs. 9 and 10 the connection between the evener-roll C and the feed-wheel shaft P 100 is made directly by expansion-gears or long-toothed gears c³ p⁷ on said roll and shaft, respectively, which permit of a sufficient variation of the distance between the centers of said roll and shaft without disengagement of 105 said gears c³ p⁷.

In Figs. 11, 12, and 13 the feed-wheels p⁸ are represented as fluted cylinders of greater length than the feed-wheels in the other figures and as being journaled in brackets d², 110 cast with or otherwise secured to the under faces of the evener-plates.

The hubs are connected by links, as in Figs. 6, 7, and 8, and are driven in the same manner, the other parts shown in Figs. 11, 12, and 13 being like the parts having similar letters of reference in the other figures.

I claim as my invention—

1. The combination of a rotary evener-roll, evener-plates, wheels, having peripheries 120 adapted to engage fibers passing between said plates and roll, said wheels having their axes on the opposite side of the operative surfaces of said plates from said evener-roll and extending through said plates, and means of rotatting said wheels at substantially the same surface speed as that of said roll.

2. The combination of a rotary evener-roll, evener-plates, wheels, having peripheries adapted to engage fibers passing between said plates and roll, said wheels having their axes on the opposite side of said plates from said evener-roll and extending through said plates, and means intermediate said evener-roll and

said wheels, for rotating said wheels at substantially the same surface speed as that of said roll.

3. The combination of a rotary evener-roll, 5 evener-plates, feed-wheels, links, arranged in the intervals between adjacent wheels and jointed to the hubs of said wheels to cause said wheels to rotate each with the same speed as the others and to permit said wheels to be 10 moved independently of each other toward and away from said evener-roll, and means for rotating said feed-wheels at substantially the same surface speed as that of said evener-roll.

15 4. The combination of a rotary evener-roll, evener-plates, feed-wheels, forked levers, each supporting the hubs of one of said wheels, links, arranged in the intervals between adjacent wheels and jointed to the hubs of said 20 wheels to cause said wheels to rotate each with the same speed as the others and to permit said wheels to be moved independently of each other toward and away from said evener-roll, and means for rotating said feed-wheels 25 at substantially the same surface speed as that of said evener-roll.

5. The combination of a rotary evener-roll, evener-plates, feed-wheels, having hubs, forked levers, each supporting the hubs of one 30 of said wheels, links, arranged in the intervals between adjacent wheels and jointed to the

hubs of said wheels to cause said wheels to rotate each with the same speed as the others and to permit said wheels to be moved independently of each other toward and away from 35 said evener-roll, and gears, secured on the ends of said evener-roll, and other gears, secured to the outer hubs of the wheels at the end of said series of wheels, and engaging said first-named gears to rotate said feed-wheels by the rotation of said evener-roll. 40

6. The combination with the feed-rolls and feed-apron of an evener-roll, evener-plates, feed-wheels, having their centers on the opposite side of said plates from said evener-roll, said feed-wheels having curved surfaces adapted to engage fibers passing between said evener-roll and said evener-plate, and said feed-wheels extending through said evener-plates, and means of rotating said feed-wheels 45 at substantially the same surface speed as that of said evener-roll, said evener-roll, evener-plates and feed-wheels being all arranged between said feed-rolls and feed-aprons. 50

In witness whereof I have signed this specification, in the presence of two attesting witnesses, this 10th day of September, A. D. 1897. 55

ALONZO A. COBURN.
